UNITED STATES PATENT OFFICE

MARIE M. GUTSCHE, OF ST. PAUL, MINNESOTA

DESIGN FOR LAUNDRY FINGERS

Application filed April 19, 1933. Serial No. 47,837. Term of patent 14 years.

To all whom it may concern:

Be it known that I, MARIE M. GUTSCHE, a citizen of the United States, residing at St. Paul, county of Ramsey and State of Minnesota, have invented a new, original, and ornamental Design for Laundry Fingers, of which the following is a specification, reference being had to the accompanying drawing forming part thereof:

Figure 1 is a perspective view showing my new design partly in an open position.

Figure 2 is a side view of my new and ornamental design for laundry fingers.

Figure 3 is a plan view of the same.

Figure 4 is an edge view, looking at the apexes of the fingers.

Figure 5 is a section on the line 5—5 of Figure 2.

I claim:

The ornamental design for laundry fingers, substantially as shown.

MARIE M. GUTSCHE.
